SPECTACLE ENDPiece

Otto Emil Wolter, Chicago, Ill., assignor to Dr.
Ritholz & Sons Company, Chicago, Ill.

Application September 15, 1949, Serial No. 5,004

Term of patent 7 years

(Cl. D57—1)

To all whom it may concern:

Be it known that I, Otto Emil Wolter, a citizen of the United States and resident of Chicago, in the county of Cook and State of Illinois, have invented a new, original, and ornamental Design for a Spectacle Endpiece, of which the following is a specification, reference being had to the accompanying drawing, forming a part thereof.

Fig. 1 is an enlarged perspective view of a spectacle endpiece, showing my new design;

Fig. 2 is an outside elevational view;

Fig. 3 is a top plan view;

Fig. 4 is a rear elevational view; and

Figs. 5 and 6 are opposite end views thereof.

I claim:

The ornamental design for a spectacle endpiece, substantially as shown.

OTTO EMIL WOLTER.
